UNITED STATES PATENT OFFICE.

BOHDAN PANTOFLICEK, OF PILSEN, CZECHOSLOVAKIA.

METHOD OF DISCHARGING BOMBS AND FOR RENDERING THEIR FUSES ACTIVE.

Application filed October 18, 1924, Serial No. 744,899, and in Czechoslovakia October 16, 1923.

The present invention relates to a method of discharging bombs and for rendering the fuses of same active, a delay in the fuse being introduced if desired in any suitable 5 manner by the help of an electric current.

By simply switching on the electric current the bombs are prepared for being discharged and can then be discharged by the closing of contacts in any desired manner, 10 either singly or in series, with or without delayed action of the fuses. The bombs or their fuses as the case may be are kept in the safety condition and are discharged or are allowed to fall by means of the electric 15 current.

If the bombs are moved owing to any other cause, for example, if they should fall out of their receptacle or if the flying machine carrying them should be disturbed or if the 20 bombs or their fuses should be struck by enemy fire, the fuses are not rendered active and the bombs therefore cannot explode from whatever height and with whatever velocity they fall. On the other hand bombs dis- 25 charged according to the method forming the subject of the present invention are rendered active by electrical means at a short distance from the flying machine from which they are discharged so that in this way 30 bombs may in case of need be discharged with safety from low altitudes.

The bomb suspending devices are extremely simple and free from any mechanism or transmission and the bombs are dis- 35 charged by simply pressing a key which results in the immediate and pre-arranged discharging of the bomb.

Finally the discharging apparatus accord- 40 ing to the present invention can be provided with a registering device.

According to the present invention bombs or projectiles of any kind can also be discharged in any other way, for example by firing them or mechanically discharging 45 them, the electric current only serving to render the fuse active. Further, according to the present invention provision is made whereby the source of current only furnishes current to the wiring system on the flying 50 machine attaining a given speed or after having reached a given height. When the apparatus is set to work at a given speed this can be effected, in the case of a dynamo being the source of current, by means of a

propeller which drives the dynamo, or if a 55 battery is the source of current by means of a regulator driven by a propeller. When set to operate according to height the switch- 60 ing on of the current can be effected by means of a barometer. Finally, the current 65 can be switched on if desired by hand.

In the accompanying drawings the essential features of the invention are illustrated diagrammatically,

Fig. 1 illustrating an arrangement for carrying the bombs horizontally, 65

Fig. 2 an arrangement for carrying them vertically,

Fig. 3 illustrates one construction of a fuse according to the invention, 70

Fig. 3^a is a sectional view of the fuse taken on lines 3^a-3^a of Figure 3,

Fig. 4 is another construction of a fuse, 75

Fig. 5 a third construction,

Fig. 6 a fourth construction, and

Fig. 7 a fifth construction of a fuse.

Fig. 8 illustrates the wiring system for supplying electric current to the several bombs.

In Fig. 1, the bomb 1 hangs horizontally 80 upon the bracket 2, the bomb being held at one side by the plug 3 of the fuse 4 in the eye 5 and being secured in this position by the pin 6. The other side of the bomb lies with the pin 7 on the nose 8 of the bracket. 85 The current which comes from the source of current 9 is led, when the switch 10 is thrown in and the key 11 depressed, through the leads 12, 13, the contact 14 being connected with the plug 3 of the fuse 4. In 90 some cases the current may simultaneously be led through the lead 18 to the ring 17 by throwing in the switch 16, and by this means the fuse delay can be thrown into or out of action. When the circuit is closed the plug 95 3 of the fuse 5 is drawn out of the fuse in a manner described below.

By the withdrawal of the plug 3 from the fuse 4 the bomb is rendered active and it can slide in the direction of the arrow 19 100 along the projections 8 and 20 out of the cradle.

Bombs adjusted in this manner can without any other additional alteration also be used for vertical discharging devices, as 105 illustrated in Fig. 2. The electrical arrangement is exactly the same as in the foregoing example. The bomb 1 here lies supported

by means of the fuse 4 upon a swinging arm 21 which can turn about the pin 22. The arm 21 is held in the safety position by the plug 3. On the withdrawal of the plug 3 from the fuse, the fuse is rendered active and the arm 21 swings outwards in the direction of the arrow 23 and the bomb is discharged.

In Figs. 3 to 7 a number of constructions of fuses are illustrated and it can be seen from these how the withdrawal of the plug 3 from the fuse is effected and how it effects the freeing of the bomb and renders the fuse active.

In Fig. 3 the plug is thrown out of the fuse 4 by means of a powder charge 24 which is ignited by means of the electrical igniter 25. The striker *g* which bears the ignition cap 26 is held in the safety position by means of a pin 27 which rests upon a powder cylinder 28. A firing pin *n* is inserted in orifices *a* of a powder securing means *p* and held there. The striker *g* is provided with a longitudinal orifice 26 which enables the striker *g* to move in the direction of the pin *n*. By the ignition of the powder charge 24 a flame is driven through the passages 29 and 30 to the powder cylinder 28 the powder in which is ignited. After the powder in 28 has burned and pin 27 is no longer held against movement in the direction toward the head of the fuse, so that when the bomb impacts, the striker *g* with the ignition cap 26 moves against the ignition pin *n* and the said cap 26 is perforated. In order that the powder cylinder 26 may burn uniformly, or in order to delay its explosion, an expansion space 31 is inserted between the passages 29 and 30. This expansion space 31 may connect with the outside air by means of passages 32.

A similar device is also necessary with those fuses in which the removal of the plug 3 actuates a time fuse.

Fig. 4 shows a modified construction of fuse which is here constructed as a time fuse. In this case the powder mass 24 is divided by a yielding partition 33 from the fuse proper. By the ignition of the powder mass 24 the yielding partition is pressed inwards or displaced and its point 34 is caused to ignite the detonator 35 which in known manner actuates the time fuse or percussion fuse.

A further example illustrating the mechanical removal of the safety device is illustrated in Fig. 5, and here the double fuse is provided with a delay which is automatically inserted upon the projectile striking a hard body. In this case also, by means of the electrical igniter 25 the powder charge 24 is ignited and throws the plug 3 out of the fuse 4. The plug 3 takes with it a bolt 36 which closes the mouth of the plug 3 and in this case the plug is thrown out without noise. The passages 32 serve if required

for leading off the gases which may escape if the opening 37 of the plug 3 is not tightly closed by the bolt 36. By the withdrawal of the bolt 36 the striker 38 is freed and the fuse is rendered active.

The flames from the detonators 39 can pass to the cap 40 either direct in the direction of the arrow 41 or with a delay in the direction of the arrow 42. When the bomb strikes soft ground, the screws 43 which hold the slide 44, provided with an inset ring of lead 45, are not torn away and ignition or expansion takes place instantaneously. When the bomb strikes a hard substance the screws 43 are torn away and the slide 44 closes by means of the lead ring 45 the passages which run direct in the direction of the arrow 41 and this is done before the detonators 39 are pierced, since the distance to be traversed by the slide 44 to close the direct passages is less than the distance to be traversed by the striker 38. In this latter case the flames from the detonators will strike the fuse delay 46 and set it in operation.

In Fig. 6 is illustrated a fuse with a mechanically inserted delay. In this construction of the fuse the bolt 47 is displaced by the action of a spring 48 into the position indicated in dotted lines so that the striker 49 is rendered active by the balls 50 falling out. The head 51 of the bolt 47 then lies in the active position on the annular surface 52 since the plug 3 has been thrown out of the fuse and no longer holds back the bolt 47. When the fuse strikes soft ground the latter forces its way through the free opening into the space previously occupied by the plug 3 and forces the head 51 of the bolt 47 upwards. Meantime the striker 49 in view of the checking of the bomb has moved a short way forward and causes the firing of the detonator 53 almost instantaneously on the bomb striking.

When the fuse strikes a hard substance, the latter does not force its way into the space left by the removal of the plug 3 and consequently it does not raise the head 51 and bolt 47. Consequently the striker 49 is obliged to travel a longer distance so that a delay in the explosion is caused.

Finally in Fig. 7 is illustrated an example of an electrically operated fuse delay. In this case also the fuse is rendered active by the throwing out of the plug 3, the flames from the detonators 54 passing either directly through the passage 55 or by way of the delay 57. By introducing the electric current into the ring 58, the powder charge 59 is fired and this lifts the plunger 60 which presses together the lead cylinder 56 and so closes the opening 55 so that there is no longer a direct passage for the flame and the detonator flames can only operate the fuse delay 57.

The fuse used with the present invention can of course be constructed in various ways and the constructions illustrated do not exhaust the possibilities nor exclude the use of other constructions.

In Fig. 8 are illustrated the connections for the supply and control of current for bombs with electrically actuated delays.

The bombs, as also the discharging device 10 are in this case arranged in parallel with the source of current 54. If the aviator wishes to discharge bombs he throws in the main switch 55 whereby the whole system is made ready for discharging. By throwing 15 in the switches 56 to 60, either in the direction of the arrow 61 or in the direction of the arrow 62 the bombs are discharged either with or without fuse delay.

If the switches 56 to 60 are connected 20 with one another so that the movement of the switch 57 follows the movement of the switch 56 and further the movement of the switch 58 follows the movement of the switches 57 and 56, and so on, then by the 25 movement of a single switch all the bombs can be discharged which are arranged in front of this switch, all being discharged at once and with or without fuse delay. The switches can of course be made in various 30 ways either in the form of lever switches or key switches and so that one series of keys serves for discharging bombs with fuse delay whilst another series of keys discharges bombs without fuse delay. Finally both 35 kinds of keys may be employed in combination and all these switches may be replaced by a single lever or a single crank.

The bombs may be suspended in a great 40 variety of other ways, they may for example be suspended one behind the other without departing from the spirit of the invention.

I claim:

1. In an apparatus of the character described, the combination of means to support a bomb, and electric means for releasing the bomb and rendering its fuse active selectively either with or without delay and causing it to act as an impact fuse or as a 50 delay fuse.

2. In an apparatus of the character described, the combination of means to support a bomb, and electric means effecting the support to change its position to release 55 the bomb and further to render the fuse active selectively either with or without delay and causing it to act as an impact fuse or as a delay fuse, the change in position of the support by electrical means being effected by movement of certain constituent 60 parts of the fuse when a powder charge is used.

3. In an apparatus of the character described, the combination of a bomb support and electrical means for simultaneously

causing the support to release the bomb and rendering its fuse active, said bomb being provided with a plug which is forced out to render the fuse active.

4. In an apparatus of the character described, the combination of a bomb support and electrical means for simultaneously causing the support to release the bomb and rendering its fuse active, said bomb being provided with a plug which is forced out 70 to render the fuse active, said support comprising a swinging arm in which the bomb is held fast by said plug, the latter being forced out permits said arm to swing outwards and free the bomb.

5. An apparatus for discharging bombs and for rendering their fuses active as claimed in claim 4, in which an expansion space is provided between the plug and the fuse, and a connection is provided between 85 said expansion space and the outside air, so that the gases from the charge which forces out the plug do not enter the fuse.

6. An apparatus for discharging bombs and for rendering their fuses active as 90 claimed in claim 4, in which there is provided between the plug and the fuse, a deformable partition which by its movement is adapted to render the fuse active.

7. An apparatus for discharging bombs and for rendering their fuses active, as 95 claimed in claim 4, in which there is provided between the plug and the fuse a bolt adapted to act as a valve and to cut off the fuse from the gas from the charge which 100 expels the plug.

8. An apparatus for discharging bombs and for rendering their fuses active as claimed in claim 4, in which the expulsion 105 of the plug causes the removal of a safety device.

9. An apparatus for discharging bombs and for rendering their fuses active as 110 claimed in claim 4, in which a sliding member is provided in the fuse, said member being held by suitable checking means in such manner that on the bomb striking a hard substance the direct passage for the flame for firing the cap is closed.

10. An apparatus for discharging bombs and for rendering their fuses active as 115 claimed in claim 4, in which provision is made for preventing the escape of the gases which effect the expulsion of the plug.

11. An apparatus for discharging bombs and for rendering their fuses active as 120 claimed in claim 4, in which, when the plug holding the bomb is expelled, the bolt holding the striker is freed, so that when the bomb strikes soft ground the soil can enter the fuse and cause instantaneous explosion and when the bomb strikes hard ground the explosion only takes place after the striker 125 has travelled a given distance.

12. An apparatus for discharging bombs 130

and for rendering their fuses active as claimed in claim 4, wherein an element in the fuse is electrically operated which element causes the guiding of the flame from the fuse to the exploding charge.

13. An apparatus for discharging bombs and for rendering their fuses active as

claimed in claim 4 in which the source of electric current is furnished by a dynamo driven by a propeller. 10

In testimony whereof I affix my signature.

ING. BOHDAN PANTOFLICEK.
